(No Model.)

W. C. NEWMAN.
BRIDGE GUARD.

No. 442,133.

Patented Dec. 9, 1890.

UNITED STATES PATENT OFFICE.

WILLIAM CHARLES NEWMAN, OF CHARLEVOIX, MICHIGAN.

BRIDGE-GUARD.

SPECIFICATION forming part of Letters Patent No. 442,133, dated December 9, 1890.

Application filed July 10, 1890. Serial No. 358,306. (No model.)

To all whom it may concern:

Be it known that I, WILLIAM CHARLES NEWMAN, a citizen of the United States, residing at Charlevoix, in the county of Charlevoix and State of Michigan, have invented a new and useful Bridge-Guard, of which the following is a specification.

This invention relates to bridge-guards, and it may be described as being an improvement on the device for which Letters Patent of the United States No. 389,714 were granted to me on the 18th day of September, 1888.

My present invention consists in the improved construction, arrangement, and combination of parts, which will be hereinafter fully described, and particularly pointed out in the claims.

In the drawings hereto annexed, Figure 1 is a perspective view of one of the approaches 20 of a bridge embodying my improvements. Fig. 2 is an end elevation of the draw. Fig. 3 is a perspective view similar to Fig. 1, but showing the gates or guards open and indicating in dotted lines the draw in position as 25 closed.

Like numerals of reference indicate like parts in all the figures.

1 designates one of the approaches of a bridge, having an abutment 2, which may be 30 of masonry or of any suitable material and construction.

Over the foot-walks 3 of the approach are erected the gate-posts or supports, each of which is composed of two inner and two 35 outer posts, designated, respectively, by 4 and 5, and which are spanned by means of arches 6. Each foot-walk is thus virtually spanned by a double arch. Between the outer gate-posts 5 are pivoted the gate-levers 7, 40 from which the gate-bars 8 are suspended by means of links 9. One of the gate-levers is provided at its end with a metallic strap 10, the outer end of which forms a hook 11, which, when the gates are lowered, engages the end 45 of the opposite gate-lever, thus locking the gate-levers securely together and enabling them to resist any strain to which in practice they are liable to be subjected. The gates are also braced and re-enforced by the inner gate- 50 posts 4, between which they swing, and which, as will be seen, will prevent them from being readily displaced by pressure from the side of

the approach. The outer ends of the gate-levers are provided with balance weights 12.

Each of the approaches of the bridge is provided with bearings 13 for a horizontal longitudinal shaft 14, the outer end of which is bent upwardly, so as to form an arm 15, at the upper end of which a friction-roller 16 is journaled. Said shaft is also provided with a casting 17, securely keyed thereon and forming oppositely-extending arms, the ends of which are connected by chains 18, passing over suitable guide-pulleys, with the outer ends of the gate-levers. The guide-pulleys 19 to which I refer are located, respectively, at the corners of the abutment, where they are designated by 19, between the lower ends of the outer gate-posts 5, which for this purpose are extended downwardly below the foot-walk, the pulleys here located being designated by 20, and between the outer guide-posts at a short distance below the pivotal points of the gate-levers, the pulleys here located being designated by 21. It will be seen 75 that by this arrangement the pulleys 20 and 21 and that portion of the chains which is between said pulleys is eased between the posts 5, and is thus protected and rendered less liable to become disarranged.

22 designates the draw, under the ends of which are arranged the cams 23, which taper slowly and gradually from their ends to the center, as will be plainly seen in Fig. 2 of the drawings.

The operation of this invention will be readily understood from the foregoing description, taken in connection with the drawings hereto annexed. When the draw is closed, the cams 23 at the ends of the draw 90 engage the friction-rollers 16 at the ends of the arms 15 of the rock-shafts 14, thereby holding the arms of the casting 17 in an approximately vertical position, at which they are caused to pull upon the chains 18, and thereby holding the gates in an open or raised position. When the draw is open, the cams 23 will gradually pass out of engagement with the friction-rollers at the ends of the arms 15 of shafts 14, thus permitting said shafts to 100 turn in their bearings actuated by the gates which descend by gravity to a closed position, the gates being completely closed, so as to bar the approach at the instant that the cams 23

pass out of engagement with the arms 15 or with the friction-rollers at the ends of the arms. It is obvious that by making the chain 18, connecting the casting 17 with the lever 7, 5 having the hook-strap 10, slightly shorter than the chain 18, connected with the other gate-lever, the former may be caused to descend after, and ascend before, the latter, thus timing the operation, so that the hook 11 of the 10 strap 10 shall infallibly engage the end of the opposite gate-lever.

While in the drawings hereto annexed only one approach has been shown, it is obvious that the arrangement of the gates and their 15 operating mechanism is to be duplicated at each end of the bridge. I also desire to state that I reserve the right to any changes and modifications in the details of construction of the device herein described which may be 20 resorted to without departing from the spirit of my invention.

Having thus described my invention, what I claim, and desire to secure by Letters Patent of the United States, is—

25 1. The combination, with the double arches spanning the foot-walks of a bridge-approach, of the gate-levers pivoted between the outer posts of said arches, substantially as set forth.

2. The combination of the double arches 30 spanning the foot-walks of the bridge-approach, the gate-levers pivoted between the outer posts of said arches, and the metal strap secured to the end of one of said gate-levers and adapted to engage the end of the other 35 lever for the purpose of locking said levers together when lowered, substantially as set forth.

3. The combination of the double arches 40 spanning the foot-walks of a bridge-approach, the gate-levers pivoted between the outer posts of said arches, balance-weights at the outer ends of said levers, the gate-bars sus-

pended by links from said levers, and mechanism for operating the said gate-levers automatically by the opening and closing of the 45 draw, substantially as set forth.

4. The combination of the rock-shaft journaled in the abutment and having at its outer end an upturned arm carrying a friction-roller, a casting mounted upon said shaft and 50 having oppositely-extending arms, the double arches spanning the foot-walks of the bridge-approach, the gate-levers pivoted between the outer posts of said arches, the chains attached to the outer ends of said levers passing over 55 guide-pulleys journaled between the outer posts at points below the pivotal points of the levers and near the lower ends of said posts and at the corners of the abutment, the ends of said chains being attached to the ends of the casting mounted upon the rock-shaft, and the cam secured under the draw of the bridge, substantially as set forth.

5. In a bridge-guard, the combination of 60 the double arches spanning the foot-walks of the approach, the gate-levers pivoted between the outer posts of said arches, guide-pulleys pivoted between said outer posts below the pivotal points of the levers and at the lower 65 ends of said posts, which are extended below 70 the pavement, the guide-pulleys at the corners of the abutment, and the chains passing over the several guide-pulleys and connecting the outer ends of the gate-levers with arms extending from a rock-shaft journaled in the 75 abutment, substantially as set forth.

In testimony that I claim the foregoing as my own I have hereto affixed my signature in presence of two witnesses.

WILLIAM CHARLES NEWMAN.

Witnesses:

PETER SEGUIN,
SAMUEL L. PRICE.
